Primary Examiner — Catherine S Posthauer*Assistant Examiner* — Yen Le Southwood(74) *Attorney, Agent, or Firm* — Michael Best & Friedrich LLP(57) **CLAIM**

The ornamental design for a compostable cup, as shown and described.

DESCRIPTION

FIG. 1 is a lower perspective view of a compostable cup according to our new design.

FIG. 2 is a bottom view of the cup of FIG. 1.

FIG. 3 is a front view of the cup of FIG. 1; and,

FIG. 4 is a left side view of the cup of FIG. 1.

The broken lines depict portions of the compostable cup that form no part of the claimed design. The dot-dash broken lines depict boundary and form no part of the claimed design.
